UNITED STATES PATENT OFFICE.

JOHN H. KELLOGG, OF BATTLE CREEK, MICHIGAN.

DESIGN FOR A PAD FOR ABDOMINAL SUPPORTERS.

SPECIFICATION forming part of Design No. 24,977, dated December 10, 1895.

Application filed October 19, 1895. Serial No. 566,273. Term of patent 14 years.

To all whom it may concern:

Be it known that I, JOHN H. KELLOGG, a citizen of the United States, residing at Battle Creek, in the county of Calhoun and State of Michigan, have invented and produced a new and original Design for Abdominal-Supporter Pads, of which the following is a specification, reference being had to the accompanying drawing, which shows a perspective view of my invention.

My design consists in the pad, which com-

prises pear-shaped perforated plates 1 1, arranged with their broader ends uppermost, and a part 2, that extends between said plates.

What I claim is—

The design for an abdominal supporter pad, as shown and described.

JOHN H. KELLOGG.
